UNITED STATES PATENT OFFICE.

CHARLES A. HORNBURG, OF DEVINE, TEXAS.

AIR-INTAKE DEVICE.

1,255,011.

Specification of Letters Patent. Patented Jan. 29, 1918.

Application filed May 21, 1917. Serial No. 169,992.

To all whom it may concern:

Be it known that I, CHARLES A. HORNBURG, a citizen of the United States, residing at Devine, in the county of Medina and 5 State of Texas, have invented a new and useful Air-Intake Device, of which the following is a specification.

The present invention appertains to an air intake device for the carbureters of automobile and other internal combustion engines, and it is the object of the invention to provide a novel and improved device of that character for supplying heated air to the carbureter during cold weather, and adjustable to admit unheated air in various proportions, according to the weather and temperature.

Another object of the invention is to provide a simple and inexpensive attachment 20 for carbureters of the nature indicated, having simple yet effective means for regulating the inflow of cool air, and simple means for preventing the excessive inflow of air, whereby the flow of air is proportionable to 25 the suction created by the pistons of the engine.

With the foregoing and other objects in view, which will appear as the description proceeds, the invention resides in the combination and arrangement of parts and in the details of construction hereinafter described and claimed, it being understood that changes in the precise embodiment of the invention herein disclosed can be made with 35 in the scope of what is claimed, without departing from the spirit of the invention.

The invention is illustrated in the accompanying drawing, wherein:—

Figure 1 is a side elevation of the device. 40 Fig. 2 is a longitudinal section of the air regulator.

Fig. 3 is a cross section of the air regulator.

Fig. 4 is a fragmental elevation of the upper end of the intake pipe, looking at right angles to the line of view in Fig. 1.

In carrying out the invention, there is provided an upstanding air intake pipe 1 of suitable proportions, the upper inlet end 50 of which is adapted to extend to the exhaust manifold 2 of the engine, for taking in air adjacent to the exhaust manifold, whereby the air is heated. The upper end of the pipe 1 is provided at the outer side of said 55 pipe with an upstanding wing 3 to overlap the manifold 2, and cause the air to flow

along the wall of the manifold before entering the intake pipe, whereby the air is heated by said manifold. The lower end of the pipe 1 extends at an angle, as at 4, 60 and is provided with a transverse cool air inlet opening 5.

An air regulator is assembled with the lower discharge end 4 of the pipe 1, and embodies a sleeve 6 having one end fitting 65 telescopically and rotatably within the end 4 of the air intake pipe, while the other end of the sleeve 6 fits the air intake portion of the carbureter 7 similarly. The parts can be readily slid or slipped into engagement 70 and the sleeve 6 is held rotatably in place, whereby it can be turned without interference. The sleeve 6 has an outstanding annular corrugation 8 between its ends to bear against the end 4 of the air intake 75 pipe, and that end portion of the sleeve 6 which fits within the intake pipe has a transverse opening or recess 9 extending from said end and of substantially the same size as the opening 5. By turning the sleeve 6 80 between the air intake pipe and carbureter, the opening 9 thereof can be brought into registration with the opening 5, to admit cool air, and the sleeve 6 can be turned so that it will close the opening 5, to shut off 85 the flow of cool air through said opening. Thus, in cold weather, the sleeve 6 can be turned to close the opening 5, whereby all of the air will flow into the upper end of the intake pipe 1, and said air will be heated 90 to supply heated air to the carbureter, which is desirable when the temperature is low. In warm weather, the sleeve 6 is turned to bring the openings 9 and 5 into registration, whereby cool air will be admitted, the amount of cool air being controlled by bringing the opening 9 more or less into registration with the opening 5. Thus, the 95 temperature of the air supplied to the carbureter can be controlled by the rotation of the sleeve 6, to suit the weather conditions.

The air regulator is provided with a spring pressed yieldable air controlling valve, and for this purpose, the sleeve 6 has an instruck annular corrugation 10, preferably adjacent 105 to the corrugation 8 at that side thereof opposite to the opening 9. This corrugation 10 provides a seat for a flap disk valve 11, which is movable to closed position against the corrugation or seat 10 away from the 110 carbureter. In order to pivotally or hingedly mount the valve 11 within the sleeve 6,

said valve is provided at one point of its margin with a recess 12 and a hinge butt 13 within said recess and having its ends spaced from the ends of the recess. A U-shaped hinge pin 14 has its intermediate portion extending through the hinge butt 13, and the end portions 15 of the hinge pin are riveted or otherwise secured to the sleeve 6 adjacent to the corrugation or valve seat 10. The spaces between the ends of the hinge butt 13 and recess 12 accommodate the end portions of the hinge pin, and the valve 11 is slightly smaller in diameter than the diameter of the sleeve, whereby to permit of the flow of air past the margin of the valve when the valve is opened slightly. This also permits the valve to swing open freely. The valve 11 is yieldably held to its seat by means of a coiled wire retractile spring 16 having its ends looped or hooked through apertures provided in the valve 11 and sleeve 6 adjacent to the pivot of the valve and air-receiving end of the sleeve, respectively.

The valve 11 in being held closed by the spring 16, will prevent the carbureter from being gorged with air, as when the engine is started or running slowly, and as the suction is increased, the valve 11 will be drawn open farther, whereby the flow of air from the intake device into the carbureter will be substantially proportional to the air suction created by the pistons working in the engine cylinders. In this manner, the intake of air is regulated, to provide for a uniform and effective mixture of the air and atomized fuel under various conditions.

Having thus described the invention, what is claimed as new is:—

1. An air intake device embodying an air intake pipe having means at one end to fit an exhaust manifold of an engine for receiving heated air, the other end of the pipe extending at an angle and having a cool air

inlet opening, and a sleeve having one end fitting within the second mentioned end of 45 the intake pipe and provided with an opening adapted to be brought into and out of registration with the aforesaid opening by the rotation of the sleeve, the sleeve having means between its ends to bear against the 50 second mentioned end of the pipe.

2. An air intake device embodying an air intake pipe for heated air having a cool air inlet opening near its discharge end, an air regulator embodying a sleeve rotatably fitting the discharge end of said pipe and having an opening adapted to be brought into and out of registration with the aforesaid opening by the rotation of said sleeve, the sleeve having outstanding means between its 60 ends to bear against the discharge end of said pipe, and a yieldable valve within the sleeve for retarding the flow of air therethrough from said pipe.

3. An air intake device embodying an air 65 intake pipe for heated air having a cool air inlet opening near its discharge end, an air regulator comprising a sleeve having one end rotatably fitting the discharge end of said pipe and provided with an opening adapted 70 to be turned into and out of registration with the aforesaid opening, the sleeve having outstanding means between its ends to bear against the discharge end of said pipe and to provide an internal valve seat, a flap 75 valve hinged to the sleeve to swing against said seat toward said pipe, and a spring connecting said valve and sleeve for yieldably seating the valve.

In testimony that I claim the foregoing as 80 my own, I have hereto affixed my signature in the presence of two witnesses.

CHARLES A. HORNBURG.
